UNITED STATES PATENT OFFICE.

JACOB GOLDBERG, OF BROOKLYN, NEW YORK.

DESIGN FOR A CANDY CONE WITH STEM.

60,136.

Specification for Design.

Patented Jan. 3, 1922.

Application filed June 9, 1921. Serial No. 476,355. Term of patent 14 years.

To all whom it may concern:

Be it known that I, JACOB GOLDBERG, a citizen of the United States, residing in the city of New York, borough of Brooklyn, county of Kings, and State of New York, have invented a new, original, and ornamental Design for a Candy Cone with Stem, of which the following is a specification, reference being had to the accompanying drawing, forming part thereof.

My design consists of a conical shaped

body portion having a stem extending from the base of the conical body portion.

Figure 1 is a view in side elevation of a candy cone with stem embodying my invention.

Figure 2 is an end view of the same.

I claim:

The ornamental design for a candy cone with stem as shown and described.

JACOB GOLDBERG.
